UNITED STATES PATENT OFFICE.

WILLIAM C. BURRELL, OF KANKAKEE, ILLINOIS.

FORMING-MACHINE.

No. 884,464.

Specification of Letters Patent.

Patented April 14, 1908.

Application filed March 14, 1904. Serial No. 198,004.

To all whom it may concern:

Be it known that I, WILLIAM C. BURRELL, a citizen of the United States, residing at Kankakee, in the county of Kankakee and State of Illinois, have invented a new and useful Improvement in Forming-Machines, of which the following is a specification.

My invention relates particularly to machines of the general type illustrated, for instance, in Letters Patent No. 715,046, granted to Moore and Lorenz, as assignees of Hugo W. Forslund, Dec. 2, 1902, my improved machine being peculiarly advantageous for use in forming sheet-metal blanks into open vessels, such as elevator-buckets.

My primary object is to provide a machine embodying a distinct novel organization of parts, whereby simplicity of construction and automatic operation, so far as the formation of each individual bucket is concerned, are attained.

In the construction shown, the machine comprises a compound female die; a vertically reciprocating male die serving to force the blank into the compound die, thereby to impart to the blank the general shape of a bucket and force the end-forming portions of the blank to approximately their closed positions; a pair of horizontally reciprocating presser-members which serve to force the end-members of the compound die inwardly to give the required set to the metal after the ends of the bucket have been preparatorily turned during the descent of the male die; and gear-mechanism whereby, upon movement of a hand-lever, a cycle of operations is effected and the operation of the dies then suspended pending the removal of the formed bucket and the insertion of a new blank. It

may be explained here that the machine, in the preferred embodiment, also is equipped with a constantly rotating gear-wheel which receives its motion from a pinion actuated through the medium of a friction clutch, with which gear the shaft which actuates the male die and end presser-members is operatively connected manually, as desired, and automatically disconnected after the completion of each cycle of operations.

My invention is illustrated in its preferred embodiment in the accompanying drawings, in which—

Figure 1 represents a view partly in front elevation and partly in section of the improved machine, the section being taken as indicated at line 1 of Fig. 4; Fig. 2, an en-

larged plan view of a device employed in the adjustment of the reciprocating presser-members; Fig. 3, a section taken as indicated at line 3 of Fig. 2; Fig. 4, a plan view 60 of the machine; Fig. 5, a perspective view of a portion of a compound female die employed; Fig. 6, a perspective view of the male die employed; Fig. 7, a view of the right side of the machine (facing with the machine); Fig. 8, 65 a view of the cam employed for reciprocating the male die; Fig. 9, an inner view of an end member of the compound die mentioned; Fig. 10, a section taken as indicated at line 10 of Fig. 9; Fig. 11, a plan section taken 70 approximately as indicated at line 11 on Fig. 7; Fig. 12, an enlarged broken section taken as indicated at line 12 of Fig. 11; Fig. 13, a view of a detached frame-member equipped with a cam for automatically maintaining connection between the shaft which actuates the male die and the end presser-members and the rotating gear journaled upon said shaft; Fig. 14, a perspective view 80 showing the relative positions of the dies and the blank at the moment the male die is about to descend, the blank being shown in full lines and the dies in dotted lines (the end-members of the female die being omitted); Fig. 15, a similar view showing the relative 85 positions when the bucket is partially formed one of the end-members of the compound die being shown in position; Fig. 16, a perspective view showing the relative positions when the bucket is completed; Fig. 17, a section 90 taken as indicated at line 17 of Fig. 4, and showing a detail of one of the presser-members employed; and Fig. 18, a view of a key employed in the adjustment of the presser-members.

A description of the preferred construction is as follows: A represents the frame of the machine equipped at its upper portion with a transversely-extending bed A¹ which supports the compound female die employed; B, 100 a compound female die having a stationary central member B¹ and reciprocable spring-retracted end-members B², B³; B⁴, B⁵, a pair of reciprocable presser-members actuated at each cycle of operations, to force 105 the die-members B², B³ together; C, a vertically reciprocable male die carried by a cross-head C¹ moving in a guide C² and actuated by a lever C³ fulcrumed on a standard C⁴, which carries the guide C²; C⁵, a connecting rod joined to the rear end of the beam C⁶ and connected with a cross-head C⁶ movable

in a vertical guide C⁷; D, a constantly rotating shaft operated through the medium of a friction-clutch D¹ of any suitable construction, controlled by a lever D²; D³, a pinion 5 fixed on the shaft D; E, a normally inactive horizontal shaft journalized in suitable bearings E¹, E²; E³, a gear mounted idly on the shaft E and constantly rotated through the medium of the pinion D³; E⁴, (Figs. 8 and 10 11); a cam fixed to the shaft E and operatively connected by a pin E⁵ (Fig. 7) to the cross-head C⁶ which serves to actuate the lever C³; F (Fig. 12), a key movable longitudinally of the shaft E and connected with 15 a sleeve F¹ shiftable through the medium of a bell-crank lever F² projecting past the front of the frame of the machine, the free end of said lever being held normally elevated by means of a spring F³ (shown in dotted lines 20 in Fig. 7); F⁴, a frame-member (Fig. 13) provided at its central portion with a perforation for the shaft E, with a key-way F⁵ opening into said perforation, and a circular cam F⁶ at one side of the frame-member and 25 bordering on the shaft-receiving perforations E⁶, a bevel-gear fixed on the inner end of the shaft E, and serving to communicate motion through a bevel-gear E⁷, vertical shaft E⁸, spur-gear E⁹, and spur-gear E¹⁰, E¹¹, to vertical shafts E¹², E¹³, respectively; and E¹⁴, E¹⁵, 30 crank-disks secured to the upper end of the shafts E¹², E¹³, respectively, and joined by connecting rods E¹⁶, E¹⁷ to the presser-members B⁴, B⁵, respectively. 35 The frame A may be of any suitable construction, and the construction shown need not be specifically described. The bed A¹ has, as shown in section in Fig. 17, a suitable way for the presser-members B⁴, B⁵. Each presser-40 member comprises a slide provided with a head for engaging the corresponding die-member, and the slides are removably secured in place by removable plates b. Adjustably connected with each slide is a bearing b¹ which receives the pin of the connecting rod which serves to actuate the slide. Each bearing-plate b¹ may be clamped to the internal flanges or tongues b² with which the corresponding slide is provided, a screw-connected 45 top-plate b³ being employed for the purpose. For adjustment purposes, there are provided wedge-members b⁴, b⁵, b⁶ (Fig. 2). The member b⁴ may be roughly adjusted with relation to the slide by means of pins b⁷ which may be set in any desired pair of 50 two series of perforations b⁸ with which the tongues b² of the slides are provided. The members b⁴, b⁵, b⁶ are connected by clamping bolts b⁹ which connect the members b⁴ and 55 b⁶ and pass through slots b¹⁰ with which the member b⁵ is provided. Adjacent edges of the members b⁵, b⁶, are recessed, as shown at b¹¹, and the walls of said recesses are provided with a series of depressions, for the purpose 60 of receiving a key b¹² (Fig. 18) which serves 65

in the adjustment of the members b⁵, b⁶, with relation to each other.

The male die C has a cross-section corresponding with the cross-section of the bucket, and the fixed member B¹ of the female die is 70 suitably recessed to receive the die C. The ends of the die-member B¹ are open, as shown. Projecting from the ends of the member B¹ are pins b¹³ encircled by coil springs b¹⁴ and extending through perforations b¹⁵ in the end die-members, the end die-members being secured against removal from the pins by means of cotter-pins b¹⁶. The end die-members are provided at their inner vertical surfaces with recesses b¹⁷ 80 corresponding in cross-section with the cross-section of the recess in the die-member B¹, the upper portions of the end die-members being beveled at said recesses, as shown at b¹⁸. The internal walls of the die-member 85 B¹ are beveled at their upper portions, as shown at b¹⁹. The friction-clutch through which motion is imparted to the shaft D need not be described in detail, as no novelty for the clutch is claimed. 90

The key F has a projection f which moves in the slot F⁵ of the frame-member F⁴, and has a shoulder f¹ which serves to engage the cam F⁶, after the key has been shifted to lock the gear E³ to the shaft E. It will be noted that the cam F⁶ has flaring beveled surfaces f² flanking the slot F⁵, and a surface f³ lying in a vertical plane. When the lever F² is depressed, thereby shifting the sleeve F¹ to the left from the position shown in Fig. 7, the key is caused to lock the gear E³ to the shaft E, and the vertical shoulder f¹ of the key rides upon the cam F⁶ until the shaft makes a revolution, whereupon the spring F³ draws the free end of the hand-lever upwardly, 100 thereby withdrawing the key and permitting the gear E³ to rotate idly. 105

From the foregoing detailed description, the operation will be readily understood. The dies being properly secured in place, and the presser-members B⁴, B⁵, being adjusted at proper distances from the end-members B², B³ of the female die, the lever D² is employed to connect the shaft D so that it will rotate with the pulley of the clutch. In this 115 condition, the gear E³ of the driving mechanism rotates idly upon the shaft E. Blanks h may now be fed by the operative to the machine, the operative, after the insertion of each blank, pressing the hand-lever F², and thereby keying the shaft E to the gear-wheel E³, this connection being maintained during one revolution of the shaft E, whereupon the shaft is automatically disconnected from the gear-wheel. Each blank h has a rear side-forming portion h¹, end-forming portions h², h³, and a front-forming portion h⁴. The end-forming portions of the blank have beveled lower edges h⁵, which co-act with the bevel surfaces b¹⁸ of the end members of the female 120 125 130

die, as the male die descends, thereby bending the end-forming portions of the blank to their proper positions. The extreme lateral margins h^6 of the portions h^2 h^3 are bent 5 around to form flanges which overlap the corresponding margins of the front-piece h^4 .

After the descent of the male die, the latter remains within the bucket, owing to the 13 shape of the cam E^4 , while the shaft E completes its rotation and causes the presser-members B^4 , B^5 to advance and force the end-members of the female die toward each other, thereby giving to the metal of the bucket the required set.

15 It will be understood that many changes in the details of construction within the spirit of my invention may be made, hence no undue limitation should be understood from the foregoing detailed description.

20 What I regard as new, and desire to secure by Letters-Patent, is—

1. The combination of a vertically reciprocating male die, a female die having a fixed open-ended member and spring-retracted 25 slidable end-members provided with surfaces for turning the end-forming portions of the blank during descent of the male die, and mechanism equipped with reciprocating presser-members serving to force the end-members of the female die towards each 30 other after the male die has completely entered, for the purpose set forth.

2. The combination of a suitable driving mechanism, a reciprocable male die, a female die, presser-members movable longitudinally 35 of the female die, gear mechanism serving to actuate the male die and the presser-members, and connecting mechanism between the driving mechanism and gear mechanism, 40 comprising a cam-controlled clutch-member, whereby connection is maintained for a predetermined period, for the purpose set forth.

3. The combination of suitable driving mechanism, a reciprocable male die, a female die, presser-members, gear mechanism serving 45 to actuate the male die and the presser-members, and connecting mechanism between the driving mechanism and gear mechanism, comprising a manually-shifted spring-retracted cam-controlled clutch-member 50 serving to maintain connection during a cycle of operations upon the blank.

4. The combination of suitable die-members for operating upon a blank, gear mechanism through the medium whereof the die-members are actuated, driving mechanism, and connecting mechanism comprising a shiftable clutch-member, a stationary cam serving to maintain said clutch-member in 55 operative engagement with its companion member during a predetermined period, and means for shifting said first-named clutch-member at proper intervals, for the purpose set forth.

65 5. The combination of suitable die-mem-

bers for operating upon a blank, gear-mechanism through the medium whereof the die-members are actuated and including a normally inactive shaft, driving mechanism including an idly rotating gear journaled on 70 said shaft, and connecting-mechanism comprising a stationary cam having a perforation receiving said shaft, a shiftable clutch-member provided with a shoulder for engaging said cam, and means for shifting said 75 clutch-member at proper intervals, for the purpose set forth.

6. The combination of suitable die-members for operating upon a blank, gear-mechanism through the medium whereof the die-members are actuated and including a normally inactive shaft, driving mechanism including an idly rotating gear journaled on 80 said shaft, and connecting-mechanism comprising a perforate stationary cam through which said shaft passes, said cam having a lateral cam-surface with beveled portions and a key-way meeting said beveled portions, a shiftable clutch-member keyed to said shaft and having a key extending through 85 the key-way of said cam, said key having a shoulder for engaging the cam-surface, thereby to maintain connection during a revolution of said shaft, and means for manually shifting said clutch-member to effect engagement and automatically retracting said clutch-member to effect disengagement, for 90 95 the purpose set forth.

7. In mechanism of the character described, the combination of a normally inactive shaft, a normally rotating gear journaled on said shaft and provided with a key-way, a frame-member having a perforation receiving said shaft, a key-way opening into 100 said perforation, and a lateral cam bordering on said perforation, a clutch-member splined upon said shaft and provided with a key having a shoulder serving to engage said cam, a lever serving to shift said clutch-member, and potential means for shifting said lever in 105 one direction whereby said clutch-member remains normally disengaged, for the purpose set forth.

8. The combination of a suitable frame, a compound female die supported thereon and having horizontally reciprocating members, a pair of presser-members serving to force 110 said end die-members toward each other, a vertically reciprocable male die, gear-mechanism comprising a normally inactive shaft 115 equipped with a cam serving to actuate said male die, and presser-member actuating shafts geared to said first-named shaft, driving mechanism comprising a gear normally rotating idly upon said first-named shaft, and connecting mechanism comprising a clutch-member splined upon said first-named shaft, and means for controlling the movements of 120 said clutch-member, for the purpose set forth.

125 130

9. The combination of a suitable frame, a compound female die supported thereon having a stationary central member and spring-retracted end-members provided at their inner vertical surfaces with recesses corresponding in cross-section with the cross-section of the die-opening in the central member, said recesses of the end-members having walls terminating at their upper portions in beveled surfaces, a reciprocable male die, and mechanism serving first to depress the male die and then force the end-members of the female die towards each other, for the purpose set forth.
10. In a machine of the character described, the combination with a suitable frame, a female die supported thereon having a stationary central member and reciprocable end-members, horizontally-reciprocable presser-members for forcing said end-members toward each other, a vertically reciprocable male die, a lever fulcrumed on a

suitable pivot and serving to actuate the male die, a horizontal shaft equipped with a cam serving to actuate said lever, vertical shafts geared to said first-named shaft, and connecting means between said vertical shafts and said presser-members, for the purpose set forth. 25

11. In a machine of the character described, the combination of a suitable guide, a presser-member connected with said guide comprising a hollow slide equipped with internal flanges, wedge-members supported on said flanges, a pivot-bearing engaged by one of said wedge-members and equipped with means whereby it may be clamped to said flanges, and actuating means connected with said pivot-bearing, for the purpose set forth. 30 35

WILLIAM C. BURRELL.

In the presence of—

WALTER N. WINBERG,
W. B. DAVIES.
